UNITED STATES PATENT OFFICE.

WILLIAM H. GILBERT, OF TOLEDO, OHIO.

LAWN-MOWER SHARPENER.

SPECIFICATION forming part of Letters Patent No. 692,846, dated February 11, 1902.

Application filed March 21, 1901. Serial No. 52,200. (No model.)

To all whom it may concern:

Be it known that I, WILLIAM H. GILBERT, a citizen of the United States, residing at Toledo, in the county of Lucas and State of Ohio, have invented certain new and useful Improvements in Lawn-Mower Sharpeners, of which the following is a specification.

My invention relates to means for sharpening the knives or cutters of a rotating cutter-head, such as may be found in lawn-mowers and other apparatus, and comprises a lawn-mower with a sharpening device, as a file or hone, a carrier therefor, and means for reciprocating the carrier so as to bring the sharpening device into the path of the edges of the knives of the mower and to carry it along the same during the rotation of the cutter-head, as fully set forth hereinafter and as illustrated in the accompanying drawings, in which—

Figure 1 is a plan view of a lawn-mower embodying my invention. Fig. 2 is a cross-sectional elevation. Fig. 3 is a detail sectional view of the oscillating tongue.

The frame of the mower is suitably constructed to support the lower stationary cutter-blade *a* and the shaft *b* of the revolving cutter *M*, provided with the usual spiral knives *d*, and the frame has bearings for the drive-wheels *f*, both of which carry gears engaging with pinions *e* on the cutter-shaft *b*. Across the frame extends the usual connecting-rod *B*. To the structure thus constructed I apply my sharpening or truing device in the form of a file or hone *C*, with a reciprocating carrier therefor, which supports the said device, which I shall hereinafter term the "file," in position to make contact with the edges of the rotating knives, so that as the carrier reciprocates the knife-edges will be brought to their proper alinement and sharpened so as to maintain them in effective condition or so as to bring them to effective condition if they are dull.

Any suitable carrier may be employed for supporting and moving the file; but, as shown, I make use of a carrier *G*, having at one end a recess for a cross-threaded driving-shaft or screw *N*. In order that the carrier *G* may be reciprocated by means of the cross-threaded shaft *N*, means are provided, as a screw *p*, passing through the head of the car-

rier and having a tongue *s* extending into the threads of the shaft *N*. The tongue *s* is not made integral with the screw *p*, but is adapted to oscillate or rotate in the end of said screw, thereby tending to reduce friction during the reciprocations of the carrier.

The shaft *N* is provided at both ends with friction-pulleys *h*, each of which bears against the edge of one of the wheels *f*, the shaft *N* turning in a link *n*, hooked to engage the shaft and also to engage the connecting-rod *B*, so that the pulleys *h* will, with their shaft *N*, swing about the rod *B*, maintaining the contact between the pulleys and the wheels *f*, which thus serve, as the machine is propelled forward, to impart rotation to the shaft *N* and reciprocation to the carrier *G*.

The file *C* is preferably supported on the carrier through the medium of a fork *t*, secured by a set-screw *q*, so as to be adjustable back and forth, and between the outer ends of the fork is a cross-bolt *r*, to which the file *C* is connected, so that as the cutter rotates the knives thereof may be brought into contact with and sharpened by the file.

It will be obvious that in applying my invention to mowers or machines of different kinds the carrier and its operating means will be differently constructed, and I therefore do not limit myself to the precise construction herein set forth.

Without limiting myself to the precise construction and arrangement of parts shown, I claim as my invention—

1. In a lawn-mower the combination with the cutter-head and its knives, of an attachment for sharpening said knives, which consists of a sharpening device, a carrier therefor, and means actuated by the wheels of the lawn-mower, whereby the carrier is automatically reciprocated laterally to carry the sharpening device the length of the knives, substantially as described.

2. The combination in a lawn-mower, of the rotating cutter-head, a cross-threaded driving-shaft, a carrier arranged to be reciprocated thereby, a sharpening device and means adjustably supported by the carrier for suspending the sharpening device, substantially as described.

3. The combination in a lawn-mower, of a rotating cutter-head and its knives, a sharp-

ening device for sharpening the knives, a carrier, means adjustably supported by the carrier for suspending said sharpening device, and a shaft having reverse threads and a tongue oscillating on the carrier and engaging said threads, with means actuated by the wheels of the lawn-mower for rotating the shaft, substantially as described.

4. The combination in a lawn-mower, of a rotating cutter-head, connecting-rod B, a shaft having reverse threads turning in links swinging about said connecting-rod and provided with pulleys bearing on the driving-wheels of the mower, a carrier through which the threaded shaft passes, provided with the oscillating tongue engaging the screw-thread,

and a sharpening device supported by the carrier, substantially as set forth.

5. The combination in a lawn-mower, of a rotating cutter-head, a cross-threaded driving-shaft, a carrier arranged to be reciprocated thereby, a fork adjustably supported by the carrier, and a sharpening device suspended from the fork, substantially as set forth. ²⁵

In testimony whereof I have signed my name to this specification in the presence of two subscribing witnesses.

WILLIAM H. GILBERT.
